ANTIOVERHEATING FUSE FOR SPARK PLUGS IN INTERNAL COMBUSTION ENGINES

Filed March 18, 1926

Inventor:

O. Larsson

By: Marks & Clark
Atty's.

UNITED STATES PATENT OFFICE.

OSCAR LARSSON, OF HAESTVED, DENMARK, ASSIGNOR TO GEORG HALD, OF COPENHAGEN, DENMARK.

ANTIOVERHEATING FUSE FOR SPARK PLUGS IN INTERNAL-COMBUSTION ENGINES.

Application filed March 18, 1926. Serial No. 95,761.

Internal combustion engines, in particular such used in automobiles and in ships, can, at times, owing to a discontinuation of the cooling or a reduction or a cessation of the oil-supply become so greatly heated that the pistons seize and stick, or other disturbances in the running of the respective engine occur.

The present invention provides, in order to avoid such trouble, to insert into the electric igniting system a safety fuse which, in the case of much overheating, will melt and will, thereby, interrupt the electric circuit so that the engine will stop.

15 The fuse, preferably, consists of a wire or a cartridge of an easily melting metal and is inserted into the circuit of the spark plug, preferably within the spark plug itself. The diameter of such space is greater than 20 the diameter of the fuse and the latter, when melted, therefore reaches a level lower than the conductor in contact with the top of the fuse, and hence the circuit is thus interrupted.

25 In the accompanying drawing the invention is shown by way of example.

The figures shows a spark plug in vertical longitudinal section with an anti-overheating cartridge fitted in the porcelain part.

30 In the drawing the numeral 1 indicates the central porcelain body with a shoulder 2 locked between the conducting member 3 and a packing nut 4. The porcelain body 1 has a central channel into the lower end of 35 which a conducting member 5 is fused.

In its upper part this channel is of a larger diameter and here a fuse 6 of easily melting metal is inserted. This fuse bears against the upper end of the conductor 5 while at its top it is in conductive contact 40 with a conductive bar 7 which is, again, conductively connected with the terminal 8.

The current normally flows from the terminal 8 through the bar 7, the fuse 6 the conductor 5 and thence jumps over to the 45 part 3, which is screwed into the cylinder of the engine and therefore in conductive connection with the latter and the other pole of the source of current.

Should, now, the spark plug become too 50 warm, either because the cooling fails, or because the oil supply ceases, the fuse 6 will melt and fall, thus interrupting the circuit.

Having now described my invention, what 55 I claim as new and desire to secure by Letters Patent is:

In combination with a spark plug, a safety fuse comprising a low temperature melting metal disposed in a central channel 60 in the porcelain body of the spark plug between its central conductor and the terminal, the diameter of said channel being greater than the diameter of the safety fuse, whereby the safety fuse when melted assumes a lower 65 level than the conductor in contact with the top of the fuse, thereby interrupting the circuit.

In testimony whereof I affix my signature.

OSCAR LARSSON.
